DESK PAD OR SIMILAR ARTICLE

William E. L. Bunn, Fort Madison, Iowa, and James V. Vevirit, Kenmore, N.Y., assignors to W. A. Sheaffer Pen Company, Fort Madison, Iowa, a corporation of Delaware

Filed Nov. 13, 1963, Ser. No. 77,408

Term of patent 14 years

(Cl. D74—1)

FIG. 1

FIG. 2

FIG. 3

FIGURE 1 is a perspective view of a desk pad or similar article showing our new design;

FIGURE 2 is an enlarged front elevational view with parts thereof being shown broken away for convenience of illustration; and

FIGURE 3 is an enlarged front elevational view of a modified form thereof wherein the base portion extends to the extreme edges of the side rails.

The characteristic feature of our design resides in a substantially rectangular base portion having a pair of parallel side rails, each provided with a substantially planar top surface and substantially planar edge surfaces which are angularly disposed with respect to each other and with respect to said top surface.

We claim:

The ornamental design for a desk pad or similar article, as shown and described.
